DESIGN FOR A MOUNTING DEVICE

Maxwell Knorpp, Ozone Park, N. Y., assignor to
Knorpp Corporation, Brooklyn, N. Y., a corporation of New York

Application June 11, 1947, Serial No. 139,592

Term of patent 14 years

(Cl. D48—2)

To all whom it may concern:

Be it known that I, Maxwell Knorpp, a citizen of the United States, residing at Ozone Park, county of Queens, and State of New York, have invented a new, original, and ornamental Design for Mounting Device, of which the following is a specification, reference being had to the accompanying drawing, forming a part thereof, wherein:

Fig. 1 is a plan view of the mounting device showing my new design; and

Fig. 2 is a side elevation thereof.

I claim:

The ornamental design for a mounting device, as shown.

MAXWELL KNORPP.
